UNITED STATES PATENT OFFICE.

GEORGE W. BANKER, OF BROOKLYN, NEW YORK.

BOX-CLOSURE.

SPECIFICATION forming part of Letters Patent No. 430,106, dated June 17, 1890.

Application filed April 10, 1890. Serial No. 347,339. (No model.)

To all whom it may concern:

Be it known that I, GEORGE W. BANKER, a citizen of the United States, and a resident of Brooklyn, in the county of Kings and State 5 of New York, have invented certain new and useful Improvements in Packing-Cases, of which the following is a specification.

My invention has reference to improvements in packing-cases; and it relates to the 10 means employed for holding the cover of the case in place.

In the drawings the same reference-letters indicate the same parts in all the figures.

Figure 1 illustrates an elevation of my improved hasp detached. Fig. 2 illustrates an elevation of my improved hinge detached. Fig. 3 illustrates a vertical sectional view of a case with the hasp and hinge in position, taken through the medial line of the hasp 20 and hinge. Fig. 4 illustrates a front view of an alternative form of my hasp. Fig. 5 illustrates one form of my locking device detached. Fig. 6 illustrates a vertical section of my locking device detached.

25 A is the case. B is its cover.

C, Fig. 2, is my improved hinge, which comprises a piece of sheet metal D, preferably tin-plate, folded at about its medial line, (see Fig. 3,) and at the fold it has a perforation or 30 hole E punched therein, and at the parts in the rear of the fold are screw or nail holes G G.

H is a piece of metal, preferably wire, bent into substantially the form shown, the free 35 ends I I whereof are placed between the folded parts of the tin-plate D at the fold, at which place the tin-plate is given a tubular shape, as shown, to receive the ends of the wire, and they are passed inwardly into the 40 opening E and are bent forwardly or outwardly through the hole, as at I' I'. Thus the wire part of the hinge is locked in place and cannot spring outwardly or separate from the folded tin-plate part thereof.

45 In Fig. 1 I show my improved hasp. It has a bent tin-plate part K, substantially the same as the part D of the hinge, and also a bent-wire part L, somewhat the same as the part H of the hinge, excepting that the part L 50 of the hasp is preferably longer and the parallel sides thereof are closer together. The free ends of the wire L are attached to the folded

tin-plate part K in the same manner as in the case of the hinge, the free ends M M thereof being locked in the perforation or 55 hole N in the same manner.

O is the locking device. It consists of a piece of suitable material, preferably metal, having a hole P at one end for the reception of a nail or screw, and a shank-section Q and an undercut part R, preferably provided with a groove S (see Fig. 6) crosswise of the shank, adapted to receive the wire L, and a projecting part T, which overlaps the wire, and whereby the locker can be more conveniently 65 pushed to the right or left, as the case may be, for unfastening it.

The operation of my improvements is as follows, special reference being had to Figs. 1, 2, and 3: The hinge is fastened to the box 70 and its cover by nails or screws U, passing through the holes G into the wood of the case or cover, as may be, and if nails be used they may be clinched, as shown. The other or wire part of the hinge is fastened by two staples 75 V V, which straddle the wire and are driven through the wood of the case and clinched. The hasp is in like manner fastened by nails or screws W, and the free or swinging end L thereof is adjusted during the fastening operation so as to lie adjacent to the side of the case. The locker O is then screwed to the case between the parallel sides of the swinging end of the hasp, and the construction, size, and location of these parts relative to 85 each other are such that when the locker is swung either to the left or the right it will come in contact with the sides of the swinging hasp L and cannot move farther unless they be pressed aside, and they are made of 90 elastic wire or equivalent material so stiff that this will require considerable force, and the adjustment is also such that the locker will rest in its normal locking position (shown in Figs. 1, 3, and 4) without exerting much 95 pressure upon the swinging clasp. It will thus be seen that in order to unhasp the cover to open the case it is necessary to press the locker forcibly sidewise, bending both of the arms of the swinging hasp until it attains a 100 position in which it extends upwardly and away from the bent end of the hasp, as shown in Fig. 4, and the resistance of the hasp is such that this will not occur unless intention-

ally. It will also be seen that by my improved hinge I allow considerable freedom of movement to the cover when unhasped. Thus wrenching or similar injury to it is not so apt 5 to occur as when the more rigid forms of hinge are used.

The swinging hasps may be held in their place at their hinged ends by staple *a a*, Fig. 4, embracing the laterally-bent ends of the 10 hasp, if desired. I prefer the bent-tin pieces D, however.

In Figs. 1 and 4 I show that part of the locker in which the groove is made, which fits over the wire of the hasp as flattened or 15 spread laterally. (See *b b*, Fig. 1.) I prefer this construction because then the operation of pressing the locker sidewise against the stress of the swinging hasp is, I think, more smoothly accomplished. The locker may, 20 however, be a substantially-straight bar, as shown in Fig. 5.

I do not limit myself to the exact details of construction shown, because certain modifications may be made in the various parts and 25 still the essentials of my invention be present. By it I secure, as I believe, means whereby a cover may be attached to its case more securely, more economically, and more compactly than by any other means heretofore 30 known.

A special advantage in my form of hinge is that I can very cheaply make a hinge so broad that in many instances one hinge will take the place of two as now made, and 35 there will be no danger of the hinge coming

apart, because the free ends of the wire are locked in the perforation or hole in the sheet-metal piece.

I claim—

1. A packing-case having fastening devices 40 comprising, essentially, an open swinging hasp, a pivoted locker located between the sides of the hasp and arranged to crowd against the hasp during the locking and unlocking operation, and a hinge formed of 45 folded sheet metal perforated at the fold, and a bent wire or strip of metal embraced in the fold of the sheet metal, the free ends whereof are locked in the perforation at the fold, substantially as set forth. 50

2. A packing-case having a hinge composed, essentially, of a folded piece of sheet metal perforated near the fold and a bent wire or strip of metal inclosed within the fold, the free ends whereof are locked within the said 55 perforation, substantially as set forth.

3. A packing-case having a hinge at one side of the cover and at the other an open swinging hasp and a pivoted locker located between the sides of the hasp and arranged to 60 crowd against the sides thereof during the locking and unlocking operation, substantially as set forth.

Signed at New York, in the county of New York and State of New York, this 9th day 65 of April, A. D. 1890.

GEO. W. BANKER.
